UNITED STATES PATENT OFFICE.

VINCENZO DI MAGGIO, OF NEW YORK, N. Y.

SHOE-SUPPORT.

1,346,008.

Specification of Letters Patent.

Patented July 6, 1920.

Application filed April 5, 1919. Serial No. 287,875.

To all whom it may concern:

Be it known that I, VINCENZO DI MAGGIO, a subject of the King of Italy, residing at New York, in the county of New York and State of New York, have invented certain new and useful Improvements in Shoe-Supports; and I do hereby declare the following to be a full, clear, and exact description of the invention, such as will enable others skilled in the art to which it appertains to make and use the same.

This invention relates to shoe supports and more particularly to that type of support for holding shoes while they are being polished or while other operations are being performed upon them.

It is one of the objects of the present invention to provide a simple, inexpensive, practicable, durable and substantial device of this type which provides for the necessary adjustment of the shoe receiving part or form so as to enable it to fit shoes of various sizes. Another object of the invention is to provide for the convenient folding or arranging of the device so that it will be disposed of so that it will not occupy valuable space in a shop or room.

With these and objects in view as will be rendered and manifest from the following specification, the invention consists of the construction, the combination, and in detailed arrangements of the parts, as more particularly hereinafter described, relative to the embodiment of the invention, illustrated in the accompanying drawings in which—

Figure 1 is a perspective view of the complete device arranged ready for use,

Fig. 2 is a vertical central section through the device,

Fig. 3 is a vertical section on line 3—3 of Fig. 2,

Fig. 4 is an elevation, partly in section, of a modified construction of swivel connection.

In this embodiment of my invention, I have provided a stationary bracket or supporting member 2, having an upright or vertical pin 3 to receive the hub 4 of a horizontally extending arm 5 which forms a bracket adapted to be swung in a horizontal plane about the pivot 3. The front or swinging end of the bracket 5 is provided with an

aperture 6 to receive a screw or pin 7 threaded at its upper end to receive a nut 8. The pin or screw 7 is mounted or formed as a part of the top 9 of the rear or heel section 10 of the shoe form which also includes the front or toe section 11 which has a top and horizontal tubular or bearing part 12 slidably fitting a stem or shank 13 extending from the front of the part 10 and disposed beneath the top 9 of the form. The toe section 11 is designed to be secured in suitable relative position with respect to the heel section 10 by means of a lock or set screw 14 passing through the tubular part 12 and bearing on the fixed stem 13 of the heel section of the form. 15 and 16 are set screws for maintaining adjustment.

From the above it will be seen that I have provided an extremely simple, practicable and substantial device having a very large range of adjustment both as to the size of shoe and also as to the capacity of manipulation of the shoe so as to enable it to be readily handled for the different operations to be performed. It is understood that various changes or alterations and the desired proportion of parts may be resorted to within the spirit of the invention and scope of the appended claims.

Fig. 4 is a sectional view showing a slightly modified form from that shown in Fig. 1. The top 9 of the rear or heel section 10 instead of having a threaded pin 7 carried integral with it, has a round bolt 7' passing through the aperture in the end of the arm 5, numbered 6', which bolt has a reduced lower end to which the top 9 of the heel section 10 is adapted to be secured by means of a nut 8'.

Having thus described this invention I claim:

1. A device of the character described, comprising a fixed bracket support; a bracket arm pivoted thereon to swing in a horizontal plane; and a sectional shoe form, the heel part of which has an angular top turnably supported on the swinging end of the arm, and having therebelow a horizontal shank on which the toe section is slidably adjustable to vary the length of the foot part of the form.

2. A device of the character described, comprising a fixed bracket support; a

bracket arm pivoted thereon to swing in a horizontal plane; and a sectional shoe form, the heel part of which has an angular top turnably supported on the swinging end of the arm, and having therebelow a horizontal shank on which the toe section is

5

slidably adjustable to vary the length of the

foot part of the form, the pivot axis of the form on the arm passing in front of the ankle part of the form to facilitate manipulation of the shoe on the form. 10

In testimony whereof I affix my signature.

VINCENZO DI MAGGIO.
